(12) **United States Design Patent** (10) **Patent No.:** **US D902,896 S**
(45) **Date of Patent:** **** Nov. 24, 2020**

(54) **ANTENNA**(71) Applicant: **Antennas Direct, Inc.**, Ellisville, MO (US)(72) Inventors: **Corey Feit**, St. Louis, MO (US); **John Edwin Ross, III**, Moab, UT (US); **Richard E. Schneider**, Wildwood, MO (US)(73) Assignee: **Antennas Direct, Inc.**, Ellisville, MO (US)(**) Term: **15 Years**(21) Appl. No.: **29/741,848**(22) Filed: **Jul. 16, 2020****Related U.S. Application Data**

(60) Division of application No. 29/732,321, filed on Apr. 23, 2020, now Pat. No. Des. 892,096, which is a division of application No. 29/713,648, filed on Nov. 18, 2019, now Pat. No. Des. 883,265, which is a continuation-in-part of application No. 29/627,951, filed on Nov. 30, 2017, now Pat. No. Des. 868,720, which is a continuation of application No. 29/580,049, filed on Oct. 5, 2016, now Pat. No. Des. 809,490, which is a continuation-in-part of application No. 14/308,422, filed on Jun. 18, 2014, now abandoned, which is a continuation-in-part of application No. 13/759,750, filed on Feb. 5, 2013, now Pat. No. 8,994,600, and a continuation-in-part of application No. 29/430,632, filed on Aug. 28, 2012, now abandoned, which is a continuation-in-part of application No. 29/376,791, filed on Oct. 12, 2010, now Pat. No. Des. 666,178, and a continuation-in-part of application No. 12/606,636, filed on Oct. 27, 2009, now Pat. No. 8,368,607, which is a continuation-in-part of application No. PCT/US2008/061908, filed on Apr. 29, 2008, and a continuation-in-part of application No. 29/305,294, filed on Mar. 17, 2008, now Pat. No. Des. 604,276, which is a continuation of application No.

12/050,133, filed on Mar. 17, 2008, now Pat. No. 7,609,222, and a continuation-in-part of application No. 12/050,133, filed on Mar. 17, 2008, and a continuation-in-part of application No. 12/040,464, filed on Feb. 29, 2008, now Pat. No. 7,839,347, and a continuation-in-part of application No. 29/304,423, filed on Feb. 29, 2008, now Pat. No. Des. 598,433.

(57) CLAIM

The ornamental designs for antenna, as shown and described.

DESCRIPTION

FIG. 1 is a perspective view of an antenna, showing our new design;

FIG. 2 is a back perspective view of the antenna shown in FIG. 1;

FIG. 3 is a front view of the antenna shown in FIG. 1;

FIG. 4 is a back view of the antenna shown in FIG. 1;

FIG. 5 is a right side view of the antenna shown in FIG. 1;

FIG. 6 is a left side view of the antenna shown in FIG. 1;

FIG. 7 is a top view of the antenna shown in FIG. 1; and,

FIG. 8 is a bottom view of the antenna shown in FIG. 1.

In the drawings, the details shown in broken lines depict portions of the antenna that form no part of the claimed design.
